US00D755829S

(12) **United States Design Patent**
Kimura et al.

(10) **Patent No.:** US D755,829 S
(45) **Date of Patent:** ** May 10, 2016

(54) **DISPLAY SCREEN OR PORTION THEREOF
WITH GRAPHICAL USER INTERFACE**

(71) Applicant: **Hitachi, Ltd.**, Chiyoda-ku, Tokyo (JP)

(72) Inventors: **Tomoki Kimura**, Yokohama (JP); **Taiki Eiraku**, Tokyo (JP)

(73) Assignee: **Hitachi, Ltd.**, Tokyo (JP)

(**) Term: **15 Years**

(21) Appl. No.: **29/548,793**

(22) Filed: **Dec. 16, 2015**

(30) **Foreign Application Priority Data**

Oct. 30, 2015 (JP) 2015-024292

(51) **LOC (10) Cl.** **14-04**

(52) **U.S. Cl.**

USPC **D14/486**

(57) **CLAIM**

The ornamental design for a display screen or portion thereof with graphical user interface, as shown and described.

DESCRIPTION

The sole FIGURE is a front view of a display screen or portion thereof with graphical user interface showing our new design. The broken lines showing the display screen forms no part of the claimed design.

1 Claim, 1 Drawing Sheet
